UNITED STATES PATENT OFFICE.

ADOLPH RUBIN, OF ST. LOUIS, MISSOURI, ASSIGNOR TO SIEBER PRODUCTS MFG. CO., OF ST. LOUIS, MISSOURI, A CORPORATION OF MISSOURI.

LOOSE-LEAF BINDER.

1,350,422.

Specification of Letters Patent. Patented Aug. 24, 1920.

Application filed February 26, 1919. Serial No. 279,280.

To all whom it may concern:

Be it known that I, ADOLPH RUBIN, a citizen of the United States, residing at St. Louis, Missouri, have invented a certain

5 new and useful Improvement in Loose-Leaf Binders, of which the following is a full, clear, and exact description, such as will enable others skilled in the art to which it appertains to make and use the same.

10 This invention relates to loose leaf binders of the type in which the leaves are retained in position by tapes, bands or cords that are connected to a winding shaft which can be turned in one direction to tighten the tapes, 15 and thus cause the leaf clamping members of the binder to clamp the rear edge portions of the leaves securely together.

One object of my invention is to provide a loose leaf binder of the general type referred to which is so constructed that it is impossible to turn the winding shaft rearwardly far enough to cause the tapes to be reversed and wound onto said shaft improperly.

25 Another object is to provide a loose leaf binder of the general type referred to, in which the winding shaft is locked securely by a mechanism comprising a rigid pawl, and a spring for normally holding said pawl 30 in engagement with a ratchet wheel on the winding shaft, said locking mechanism being so constructed that the pawl will remain in engagement with the ratchet wheel on the winding shaft, even though the spring that 35 exerts pressure on said pawl breaks or loses its resiliency.

Another object is to provide a loose leaf binder of the general type referred to, in which the winding shaft is normally locked 40 by a mechanism that can be rendered inoperative only by means of a key that is used to turn the winding shaft, thereby producing a loose leaf binder in which the leaves cannot be removed or additional leaves inserted by an unauthorized person.

And still another object is to provide a loose leaf binder of the general type referred to, in which the winding shaft and the locking mechanism for the winding shaft are 45 supported by and arranged inside of a back composed of a plurality of rigid sections hinged or pivotally connected together. Other objects and desirable features of my invention will be hereinafter pointed out.

Figure 1 of the drawings is an end elevational view of a book equipped with a loose leaf binder constructed in accordance with my present invention. 55

Fig. 2 is a horizontal sectional view, taken on the line 2—2 of Fig. 1. 60

Fig. 3 is an end elevational view, showing the book open.

Figs. 4, 5 and 6 are transverse sectional views, taken on the lines 4—4, 5—5 and 6—6, respectively, of Fig. 2; and 65

Fig. 7 is a detail sectional view, illustrating another way of mounting the leaf clamping members.

Referring to the drawings, which illustrate the preferred form of my invention, 70 A and A' designate two leaf clamping members between which the leaves B of the book are arranged, and C designates tapes or bands of flexible material that pass through slots in said leaves, said tapes being connected at one end to the leaf clamping member A and extending from said leaf clamping member through the leaves and through slots in the leaf clamping member A' to a winding shaft D that is adapted to be 75 turned in a direction to draw the tapes C taut, and thus cause the leaf clamping members to clamp the rear edge portions of the leaves B together. The binder is provided with a back that is composed of a plurality 80 of rigid sections or members hinged or pivotally connected together in such a manner that the back as an entirety has sufficient flexibility to permit the leaves to open out flat in substantially the same manner as a 85 binder provided with a flexible back of fabric or other similar material. In the form of my invention herein illustrated the back of the binder is composed of two sections E and E' that are pivotally connected 90 together by a pintle 1 that passes through cooperating staggered bearings 2 on the sections E and E' of the back. The sections E and E' of the back are preferably provided at their free edges with flanges 3 to 100 which the covers F and F' of the binder are hinged by pintles 4 that pass through cooperating bearings on the flanges 3 and on said covers.

The leaf clamping members A and A' can 105 either be rigidly connected to the flanges 3 on the sections of the back, as shown in Fig. 7, or said leaf clamping members can be con-

nected to the back in such a manner that they can move relatively to the back during the operation of opening the binder, and thus assume a position in which they do 5 not form bends in the leaves or prevent the leaves from lying flat. I prefer to pivotally mount the leaf clamping members A and A' on the pintles 4 so that when the binder is opened the pressure which the 10 leaves exert on the leaf clamping members causes said leaf clamping members to swing on their axes, as shown in Fig. 3, and thus cause the portions of said leaf clamping members that bear against the rear edges 15 of the leaves to exert upward pressure on the leaves.

The winding shaft D is rotatably mounted in bearings 7 arranged on the inner side of the section E' of the back, and a mechanism of novel construction is provided for locking said shaft so as to hold the tapes C taut. Said locking mechanism consists of a rigid pawl 8 that coöperates with a ratchet wheel 9 on the winding shaft D, and a spring 25 10 that normally exerts pressure on the pawl 8 in a direction tending to hold it in locking engagement with the ratchet wheel 9. The pawl 8 is loosely mounted on a releasing shaft 11 that extends parallel to the winding 30 shaft D and which is mounted in suitable bearings arranged on the inside of the section E' of the back. The shaft 11 is provided at its outer end with a laterally-projecting arm 12 which bears against the underside of a key portion 13 on the winding shaft, and said shaft 11 is also provided at its opposite end with a pin 14 that normally bears against a lug 15 on the hub of the pawl 8. The upward pressure that the flat 35 40 leaf spring 10 exerts on the underside of the pawl 8 holds said pawl in engagement with the ratchet 9 and also causes the portion 15 on the hub of said pawl to bear against the pin 14 on the shaft 11, thereby holding the 45 50 arm 12 at the outer end of said shaft in engagement with the key portion 13 on the winding shaft D. The winding shaft can be turned in a direction to draw the tapes C taut by positioning a key G on the key portion 55 60 65 13 of the winding shaft and then turning said key in clockwise direction. It is impossible to rotate the winding shaft D in the opposite direction, or in the direction to release the tapes C, without first tripping the pawl 8 or disengaging it from the ratchet wheel 9 on the winding shaft. The release of the winding shaft is effected by forcing the key G inwardly on the key portion 13 of the winding shaft, so as to cause a cam surface 16 on said key to bear against the arm 12 on the shaft 11, and thus turn said shaft in such a direction that the pin 14 thereon will engage the portion 15 on the hub of the pawl 8 and move said pawl downwardly 65 70 75 80 85 90 95 100 105 110 115 120 125 130 out of engagement with the ratchet wheel 9.

After the locking pawl 8 has been rendered inoperative in the manner above described, the key G can be turned so as to rotate the winding shaft D in a direction to slacken the tapes C. As soon as the winding key G 70 is removed from the winding shaft or withdrawn sufficiently to disengage the cam portion 16 on said key from the arm 12 on the shaft 11, the spring 10 moves the pawl 8 into engagement with the ratchet wheel 9 75 and also moves the arm 12 on the shaft 11 into engagement with the key portion 13 on the winding shaft, so as to be in readiness to coöperate with the winding key when it is again arranged on the key portion of the 80 winding shaft.

By constructing the locking mechanism of the winding shaft in this manner I reduce to a minimum the liability of an unauthorized person removing the leaves of the binder 85 or inserting additional leaves, as the only way that the locking mechanism for the winding shaft can be rendered inoperative is by inserting a special key on the key portion of the winding shaft and moving said 90 key inwardly so as to engage the part 12 that effects the release of the ratchet wheel 9 from its coöperating locking pawl 8. The key G is preferably provided with a socket of triangular shape in cross section, and the 95 key portion 13 of the winding shaft is correspondingly formed so as to eliminate the possibility of the winding shaft locking mechanism being rendered inoperative with an ordinary clock key or key provided with 100 a square socket such as the clock keys now in universal use. When the binder is locked the tapes C exert a pull on the winding shaft D in a direction tending to hold the teeth of the ratchet wheel 9 tightly against the 105 end of the pawl 8. Consequently, even though the spring 10 should break or lose its resiliency, the winding shaft will not be released. The only way that the winding shaft can be released is to exert pressure on the 110 pawl 8 in a direction to force it away from the ratchet wheel 9, and this can only be effected by means of a special key provided with a cam shaped portion 16 for engaging the arm 12 on the shaft 11. 115

In order to prevent the winding shaft D from being rotated rearwardly to such an extent that the tapes C will be reversed and wound onto the winding shaft improperly, I have provided my improved binder with a 120 locking device that prevents the winding shaft from being rotated rearwardly or in anti-clockwise direction after said shaft has been turned rearwardly far enough to slacken the tapes C sufficiently to receive the 125 maximum number of leaves for which the binder is designed. Said locking device consists of a nut 17 mounted on a screw-threaded portion 18 on the winding shaft D and provided with a stem 19 arranged par- 130

allel to the winding shaft and passing through stationary guides 20, as shown in Fig. 2. When the winding shaft is rotated rearwardly the nut 17 will travel in the direction indicated by the arrow in Fig. 2 and come into engagement with one of the bearings 20 through which the stem 19 on the nut passes before the shaft is turned rearwardly far enough to reverse the tapes, the engagement of said nut 17 with the bearing 20 causing the winding shaft to be locked securely and held against further rotation in anti-clockwise direction.

Having thus described my invention, what I claim and desire to secure by Letters Patent, is:

1. A loose leaf binder provided with flexible devices for retaining the leaves in position, a manually operable winding shaft that is adapted to be turned in one direction to tighten said flexible devices and in the opposite direction to slacken said devices, and means for preventing said winding shaft from being turned far enough in the opposite direction to reverse said devices and wind them onto said shaft improperly.

2. A loose leaf binder provided with flexible leaf retaining devices, a manually operable winding shaft that is adapted to be turned in one direction to tighten said devices, and in the opposite direction to slacken said devices, and means that permits said winding shaft to be turned in the opposite direction sufficiently to slacken the leaf retaining devices but not far enough to disarrange said devices.

3. A loose leaf binder provided with a manually operable winding shaft, leaf retaining devices actuated by said shaft, and a locking device for said shaft that does not interfere with the rotary movement of said shaft in one direction but which causes said shaft to become locked after it has been rotated a certain distance in the opposite direction.

4. A loose leaf binder, comprising a manually operable winding shaft, leaf retaining devices actuated by said shaft, a locking device for said shaft mounted on a screw-threaded portion of said shaft, and means for causing said device to lock said shaft after it has been rotated a certain distance in one direction.

5. A loose leaf binder, comprising a manually operable winding shaft, leaf retaining devices actuated by said shaft, a locking device mounted on a screw-threaded portion of said shaft, means for preventing said device from rotating with said shaft, and a part with which said device coöperates to lock said shaft after said shaft has been turned a certain distance in one direction.

6. A loose leaf binder, comprising tapes for retaining the leaves in position, a manually operable winding shaft for tightening

said tapes, and means for limiting the rotation of said shaft in the direction to release said tapes consisting of a device mounted on a screw-threaded portion of said shaft, means for preventing said device from rotating with the shaft, and a stationary abutment against which said device strikes after said shaft has been rotated a certain distance in the direction to slacken said tapes.

7. A loose leaf binder, comprising tapes for retaining the leaves in position, a manually operable shaft for actuating said tapes, a locking device mounted on a screw-threaded portion of said shaft, a stem on said device arranged parallel to said shaft and passing through stationary bearings so as to prevent said locking device from turning with the shaft on which it is mounted, and a stationary abutment against which said device strikes after said shaft has been rotated a certain distance in one direction.

8. A loose leaf binder, comprising tapes or bands for retaining the leaves in position, a winding shaft for tightening said tapes, a rigid pawl that coöperates with a ratchet on said shaft to lock said shaft, a releasing device on which said pawl is pivotally mounted, and means for causing said pawl to be disengaged from said ratchet when said releasing device is moved in one direction.

9. A loose leaf binder, comprising tapes or bands for retaining the leaves in position, a winding shaft for tightening said tapes, a rigid pawl that coöperates with a ratchet on said shaft to lock said shaft, a releasing device on which said pawl is pivotally mounted, a portion on said releasing device being arranged in such a manner that it can be engaged by the key used to turn the winding shaft, and a spring that normally holds said pawl in engagement with said ratchet and the portion on said releasing device in position to coöperate with said winding key.

10. A loose leaf binder provided with tapes or bands for retaining the leaves in position, a winding shaft for said tapes provided with a key portion that is adapted to receive a removable key, a rigid pawl that coöperates with a ratchet on said shaft to lock the shaft, a releasing shaft on which said pawl is pivotally mounted and provided with an arm that is normally positioned adjacent the key portion on the winding shaft, means on said releasing shaft that engages said pawl and trips it when said releasing shaft is turned in one direction by the engagement of the key with the arm on said releasing shaft, and a spring for restoring said releasing shaft to its normal position and for moving said pawl into engagement with said ratchet.

11. A loose leaf binder, comprising tapes or bands for retaining the leaves in position,

- a winding shaft for tightening said tapes, a locking mechanism for said winding shaft, and a removable key that is adapted to be arranged in operative position on said 5 winding shaft and then moved longitudinally of said shaft to release said locking mechanism and thereafter retracted when it is desired to turn said shaft, said locking mechanism being so constructed that it can 10 not be rendered inoperative when said key is not in operative position on the shaft.
12. A loose leaf binder provided with a back composed of a plurality of rigid sections hinged or pivotally connected together, 15 leaf clamping members carried by said back, tapes or bands for causing said leaf clamping members to securely clamp the leaves together, and a winding shaft and locking mechanism for said shaft arranged inside 20 of and supported by said back.
13. A loose leaf binder provided with a back composed of a plurality of rigid sections hinged or pivotally connected together, pivotally mounted leaf clamping 25 members carried by said back, tapes or bands for causing the leaf-clamping member to retain the leaves in position, and a winding shaft and locking mechanism for said shaft arranged inside of and supported by 30 said back.
14. A loose leaf binder provided with tapes or bands for retaining the leaves in position, a winding shaft for tightening said tapes, means for preventing said winding 35 shaft from being rotated rearwardly far enough to reverse the tapes or cause them to be arranged improperly on said shaft, a rigid pawl that coöperates with a ratchet on said winding shaft, and a releasing de- vice for tripping said pawl so as to release 40 said winding shaft.
15. A loose leaf binder provided with tapes or bands for retaining the leaves in position, a winding shaft for tightening said tapes, means for preventing said winding shaft from being rotated rearwardly 45 far enough to reverse the tapes or cause them to be arranged improperly on said shaft, a rigid pawl that coöperates with a ratchet on said winding shaft, a releasing device for said pawl provided with an arm that is normally positioned in proximity to a key portion on said winding shaft, and a removable winding key provided with means that engages said arm to release said 50 pawl when said winding key is positioned on the winding shaft.
16. A loose leaf binder, comprising tapes or bands for retaining the leaves in position, a winding shaft adapted to be turned in one 60 direction to tighten said tapes, a locking device mounted on a screw-threaded portion of said shaft for limiting the movement of said shaft in the direction to slacken said tapes, means for preventing said locking device from rotating with said shaft, a rigid pawl that coöperates with a ratchet on said winding shaft, a releasing device on which said pawl is pivotally mounted, a spring 65 that normally holds said pawl in engagement with said ratchet, and means for disengaging said pawl from said ratchet when said releasing device is moved in one direction, said releasing device comprising a part that normally lies in proximity to a key 70 portion on said winding shaft.

ADOLPH RUBIN.
